ROTARY JAR

Guy P. Ellis, Lake Charles, La.

Application February 21, 1950, Serial No. 145,426

1 Claim. (Cl. 255—27)

1

This invention relates to a jar for use in drilling wells such, for example, as oil wells.

In connection with the drilling of oil wells numerous devices have been employed in the past for removing packers which often become stuck after remaining in oil wells for some time, by the process of jarring the implement, but in all such devices it has been necessary to first remove the tubing, by cutting or other means, and then run in the jars in connection with some type of fishing tool.

A principal object of the present invention is to provide an improved jarring device which is designed to be installed in an oil well in connection with the production string, which is commonly referred to as the tubing and packer, where such jarring device remains until such time as it may be required for use in the event that the packer becomes stuck.

Another object of the invention is to provide an improved jarring device for use in the manner above-stated, which is designed in a novel manner whereby all of the working parts are maintained enclosed and sealed in a lubricant to prevent corrosion so that the device may remain in the well over an indefinite period of time without in any way becoming damaged or unfit for use.

Other objects and advantages of the invention will become apparent as the description of the same proceeds and the invention will be best understood from a consideration of the following detailed description taken in connection with the accompanying drawing forming a part of the specification, with the understanding, however, that the invention is not to be limited to the exact details of construction shown and described since obvious modifications will occur to a person skilled in the art.

In the drawing:

Figure 1 is a view in side elevation of a rotary jar constructed in accordance with the present invention and shown installed in a production string.

Figure 2 is a longitudinal section taken substantially on the line 2—2 of Figure 1.

Figure 3 is a transverse section taken on the line 3—3 of Figure 1.

Figure 4 is a longitudinal section in a plane perpendicular to the plane of Figure 2 and showing the hammer freed and raised to the top of the barrel.

Figure 5 is a view in side elevation of the barrel per se.

Referring more particularly to the drawing the numeral 10 designates the lower portion of a production string or tubing.

2

The rotary jarring device of the present invention is connected to the lower end of the string 10 and forms a permanent part thereof. This device is generally designated 11 and it comprises 5 a long tubular hammer shank 12 which has its upper end threadably engaged in the lower end of the string as indicated at 13.

Upon the lower end of the shank 12 is the hammer 14 which is of larger outside diameter than the shank 12 and of circular cross section as shown in Figure 3. This hammer is formed at its lower end to provide the tapered valve shoulder 15 while at its upper end there is formed the encircling hammering shoulder 16, the function 10 of which will be hereinafter set forth. The shank and the hammer proper have a passage 17 extending entirely therethrough.

The hammer 14 also has formed therein the transverse slot 18 in which is located a key member 19 which extends transversely of the hammer and which has an overall length greater than the diameter of the hammer as shown in Figure 2. Thus, in the tool as assembled, the key 19 has a portion of each end projecting beyond the side 15 of the hammer 14 for the purpose hereinafter described.

The numeral 20 designates a barrel in which the hammer 14 is slidably positioned. This barrel at its lower end is of slightly reduced inside diameter as indicated at 21, whereby there is provided the annular seat 22 upon which the valve shoulder 15 rests when the tool is installed in the well hole.

The lower end of the barrel 20 is also externally reduced and screw threaded as at 23 for the attachment of a packer or another section of the well string thereto.

At its upper end the barrel has its inside diameter enlarged slightly and screw threaded as at 24 so that, as will be readily seen, the hammer may be easily inserted into the barrel.

The wall of the barrel 20 has formed therethrough the diametrically opposite longitudinal slots 25 in which the extended ends of the key 19 are engaged. These slots are straight and in line transversely of the barrel through approximately the upper half of their lengths but the lower end of each slot has an offset undercut shoulder 26 on one side while at the opposite side below the shoulder, the side of the slot is sloped to extend oblique to the length of the barrel to provide a camming surface 27. Thus it will be seen that the lower end of each slot is of increased width through a portion of its length and then slowly tapers off on one side only so that at its lower end its width is approximately the same as the upper end. The shoulders 26 are extended in

55

the same direction circumferentially of the barrel and thus it will be seen that when the hammer is in the lower part of the barrel the key will slide down the inclined camming surfaces 27 so as to turn the hammer and bring each end of the key under a shoulder 26.

After the hammer has been inserted into the barrel 20 there is threaded into the upper end of the barrel the collar 28 which was previously placed on the shank and when this collar has been threaded in as far as it will go it will be seen that it prevents the hammer from escaping from the barrel.

The inner end of the collar 28 is provided with the sloping shoulder 29 which is of the same diameter of the shoulder 16 of the hammer and this shoulder forms an anvil against which the upper end of the hammer strikes in the use of the tool.

The upper part of the collar 28 is cut out or made of an enlarged diameter as at 30 to receive a packing 31 and above the packing the collar is internally screw threaded to receive a gland nut 32 which also, of course, encircles the hammer shank 12.

Externally the barrel is of slightly reduced diameter starting just below the internally reduced portion 24 thereby forming a shoulder 33. Below this shoulder the barrel has snugly fitted thereon, the sleeve 34, the upper end of which butts against the shoulder 33 as shown. This sleeve completely covers the slots 25.

When the tool is introduced into the string, the hammer 14 is in its lowermost position so that the valve 15 will be resting upon the seat 22. In this position there are extended through the lower end of the sleeve 34, from opposite sides, the shear pins 35 which pass through the sleeve and through the lower part of the barrel and into the hammer as shown in Figure 2. Thus the hammer is secured in the lower end of the barrel 20 until such time as it becomes necessary to break the shear pins and put the jar into operation. After the hammer has been secured by the shear pins 35 in the lower end of the barrel 20, the barrel above the hammer and the slots 25, are packed or filled with suitable lubricant L and the collar 28 is then turned down to tightly close the top of the barrel whereby to prevent the lubricant from escaping. The sleeve 34 has such close fit upon the barrel as to retain the lubricant therein.

It will be readily apparent that the jarring tool normally forms a part of the well string. However, if the packer at the lower end of the jarring tool becomes stuck or frozen the tool may be put into use to release the packer, by applying the necessary upward pull on the string whereby to break or shear off the pins 35. This will release the hammer 14 which can then be drawn up to the top of the barrel 20 and during such movement the encased lubricant will escape into the lower part of the barrel by way of the slots 25.

To put the tool into use for jarring loose the packer, the string is lowered until the ends of the key 19 enter the lower ends of the slots 25 which will effect the desired partial turning of the hammer. The tool is then drawn up and, since the turning of the hammer has placed the ends of the key 19 beneath the shoulders 26, the top of the key at each end, which is slightly sloped or in-

clined as shown, will engage against the shoulders 26. By continuing the upward pull so as to firmly contact the ends of the key with the shoulders 26 and then applying a slight torque to the pipe string the key ends will disengage or slip off of the shoulders 26 and the hammer will be rapidly elevated and will come into forcible contact with the anvil 29 as shown in Figure 4. It will be readily seen that this operation may be repeated as many times as may be necessary in order to effect the loosening of the stuck packer.

It will be seen from the foregoing that there is provided in the present invention a rotary jar which can be maintained in the well hole as a permanent part of the tubing string so that when the necessity for using a jar arises it is not necessary to pull out the tubing and run in a jar on a separate line as is at present done since the production string may then be put to use for actuating the jarring tool.

While the improved jar herein set forth has been described in combination with a tubing string, and such combination constitutes a novel feature of the invention and is so claimed, it is to be understood that the invention is not intended to be limited to such combination since the jar device in itself is of novel construction and such construction is claimed apart from the combination.

I claim:

A rotary jar, comprising a barrel having a reduced inside diameter at its lower end providing an inside valve seat, the top end of the barrel having an increased inside diameter through a portion of its length, a cylindrical hammer slidably positioned in the barrel and having its lower end formed to provide a valve to position on said valve seat, a long stem carried by the hammer and extending through the top end of the barrel, a collar encircling the stem and extending into and secured in the said part of enlarged diameter at the top end of the barrel, said collar having a portion of its lower formed to provide an anvil against which the top end of the hammer strikes, means carried by the collar and encircling the stem forming a leak proof seal around the stem, said barrel having a slot longitudinally of the wall thereof, said slot being of increased width in the lower part thereof to form on one side of the slot a downwardly directed shoulder, a key extending radially from the hammer and into the slot and adapted to be engaged against said shoulder by a partial rotation of the hammer, releasable means for securing the hammer in the lower part of the barrel with the valve on the seat, a sleeve encasing the barrel and closing the outer part of the slot, and a corrosion resistant material filling the barrel above the hammer when the hammer is in the said lower part of the barrel.
